(57) CLAIM

The ornamental design for a hub structure, as shown and described.

DESCRIPTION

FIG. 1 is a perspective view of a hub structure in accordance with the invention.

FIG. 2 is a front elevational view of the hub structure of FIG. 1;

FIG. 3 is a left side view of the hub structure of FIG. 1; and, FIG. 4 is a top elevational view of the hub structure of FIG. 1.

The broken lines are included for the purpose of illustrating environmental structure and form no part of the claimed design.
